UNITED STATES PATENT OFFICE.

HENRY F. BECHMAN, OF BATTLE CREEK, MICHIGAN, ASSIGNOR TO DUPLEX PRINTING PRESS COMPANY, OF BATTLE CREEK, MICHIGAN, A CORPORATION OF MICHIGAN.

STEREOTYPE-PLATE-CASTING APPARATUS.

Application filed July 17, 1922. Serial No. 575,670.

To all whom it may concern:

Be it known that I, HENRY F. BECHMAN, a citizen of the United States, residing at Battle Creek, in the county of Calhoun and 5 State of Michigan, have invented certain new and useful Improvements in Stereotype-Plate-Casting Apparatus; and I hereby declare that the following is a full, clear, and exact description thereof, reference being 10 had to the accompanying drawings which form part of this specification.

This invention relates to machines for casting stereotype plates and is particularly designed for use in casting tubular stereotype plates for single page tubular plate 15 rotary printing presses, such as described in my Patent #979,919, dated December 27th, 1910.

The object of the present invention is to 20 provide a machine whereby such plates may be rapidly cast, wherein the casting of a plate at one point, the removal of a plate from the box and the re-charging of a box with a matrix at other points of its rotation 25 may all be performed simultaneously, and ample time given for each operation.

A further object of the invention is to 30 provide a stereotype metal pump which will deliver the proper quantity of metal into the casting box, at all times, regardless of the height of the metal in the pot.

The apparatus includes a plurality of similar stereotype plate casting boxes, preferably of the type shown in my Patent #945, 35 678, dated January 4th, 1910, mounted upon a rotatable platform or turn table; a molten metal supply and pump beside the turn table; means for rotating the turn table, preferably by an intermittent, step by step 40 movement, so as to bring the boxes successively into position to receive a charge of molten metal from the pump; novel means for controlling the movement of the said boxes to and from the casting position; 45 novel means for automatically, if desired, injecting the proper amount of molten metal into each box at the casting point; and novel means for co-ordinating the alternate movements of the turn table and the operations 50 of the metal pump, so that a proper amount

of metal will be discharged into each casting box when it is at the casting point. The invention includes other subordinate novel details of construction and novel combinations or parts, all of which will be herein- 55 after explained.

The accompanying drawings show one practical apparatus embodying the invention, and I will describe the invention as illustrated therein; and summarize in the 60 claims the essentials of the invention and the novel features of construction, and the novel combinations of parts for all of which protection is desired.

In said drawings:

Fig. 1 is a side elevation of one apparatus embodying the invention.

Fig. 2 is a top plan view thereof.

Fig. 3 is an enlarged detail side view showing the operative gearing.

Fig. 4 is a top view of Fig. 3.

Fig. 5 is an enlarged detail sectional view of the water-cooling system and turn table driving gears.

Fig. 6 is a detail view showing an adjustable pump operating crank pin.

The apparatus shown in the drawings has four stereotype plate casting boxes 1, each of which may be of any suitable construction, but is preferably constructed substantially like the casting box shown in my aforesaid Patent #945,678. Each casting box shown has a stationary drag 1^a, a hinged cope 1^b and a tiltable core 1^c such as explained in my said patent. These boxes are 80 mounted upon a rotatable platform or turn table 2 and are spaced apart 90° thereon and arranged near the periphery thereof with the copes outermost so that when the copes are opened the tiltable cores may be lowered 85 radially outward to enable the plates to be removed therefrom.

The turn table 2 is preferably supported upon an annular casting 13^a which is in turn mounted upon one end of a base plate or 90 foundation member 13. The casting 13^a has a hub portion 13^b (see Fig. 5) through which extends the hub 2^a of the turn table 2. Said turn table may be rotated by any suitable means, preferably such as will impart a 100

step by step movement thereto. In the example shown at each step or movement the table would be turned 90° .

In the construction shown a worm gear 2^b is attached to the under side of the turn table 2, concentric with the hub 2^a thereof, and is engaged by a worm 3^b on a shaft 3 which is journaled in suitable bearings 13^c mounted on the base 13. Said shaft extends longitudinally of the base 13, below the turn table 2, and on the outer end of the shaft 3 is splined a friction clutch member 3^a which is adapted to engage an opposed friction clutch member 4^a attached to a gear 4 which is rotatably mounted on the shaft 3 and is yieldingly pressed toward the member 3^a by a spring 4^d strung on shaft 3 between the hub of gear 4 and the adjacent bearing 13^c. The clutch member 3^a is slidable on shaft 3 into and out of engagement with the clutch member 4^a and may be shifted at the proper time into engagement therewith by suitable means.

As shown clutch member 3^a has a grooved hub 3^e which is engaged by the forked arm 5^e of a lever 5 pivoted at 5^a on a stationary arm or bracket 13^f attached to the support 13^a. This lever 5 carries a roller 5^e on its inner end which bears against the periphery of the turn table 2 and is adapted to successively enter notches 2^e formed in the periphery of the turn table, one notch adjacent each casting box 1. The end of lever 5 carrying roller 5^e is normally pressed toward the turn table 2 by the action of a suitable spring so that it will enter the notches when permitted. As shown, a rod 5^d is pivotally connected to the forked arm 5^e of lever 5 and passes through an eye in the bracket 13^f and a spring 5^s is interposed between the bracket and a nut on the outer end of the rod 5^d, and normally tends to rock the lever 5, and press the roller 5^e toward the disk 2, and hold the clutch member 3^a out of engagement with the clutch member 4^a.

The lever 5 may be rocked, so as to disengage the roller 5^e from the notch 2^e and slide the clutch member 3^a into engagement with the clutch member 4^a by suitable means at the proper time. Preferably this is accomplished by manual means. As shown, one end of the lever 5 is connected by a link 5^f to a hand lever 5^g which may be pivoted on the end of bracket 13^f, or other support, on base 13 in convenient position for manipulation by the hand of the operator. When the operator desires to have the turn table shifted he pulls the lever 5^g so as to rock the lever 5 against the action of spring 5^s, and move roller 5^e out of engagement with the notch 2^e and simultaneously engage clutch member 3^a with clutch member 4^a.

65 The gear 4 carrying the clutch member

4^a is normally continuously driven by suitable means during the operation of the apparatus. As shown gear 4 meshes with a pinion 6^a on a shaft 6, which is journaled in suitable bearings on the base 13, and may be driven from any suitable source of power. As shown, shaft 6 is directly connected to and driven by an electric motor 6^b, of any suitable construction, mounted on the base 13. From this shaft 6 the devices which control the pump are also operated as hereinafter described.

Water for cooling the casting boxes 1 can be supplied through a pipe 50 which enters a tubular column 2° on the turn table 2 (see Figs. 1, 2, 5) which is connected within the column, by a swivel joint 51, to a T 52 from which extend opposite radially disposed pipes 53 each of which is connected by a branch pipe 54 with two adjacent casting boxes, at opposite sides of each branch pipe 54. The other pipe 53 is similarly connected by a branched pipe 54 to the other two boxes (see Figs. 2 and 5). Thus, all four boxes are supplied with water from the one pipe 50. The hot water escapes from the boxes through branched pipes 64 each of which is connected with two adjacent boxes; and also connected with a radially disposed pipe 63, connected to a T 62 within the standard 2°, the T 62 being connected by a swivel joint 61 with a drain pipe 60 which extends down through openings in the turn table and in the base 13^a to a suitable point of discharge. This very simple arrangement provides for a continuous circulation of water to and from the casting boxes without interfering with the rotation of the turn table.

In the construction shown a stereotype metal melting pot 10, of any suitable construction, is supported on the usual furnace 10^a mounted on the base 13 adjacent the turn table 2. In this pot is a metal pump having a plunger or ladle 11 operated by a rod 11^a which may be provided with a rack 11^b engaging a pinion 11^c on shaft 11^d and at each operation of the pump the proper amount of molten metal is discharged from the pump 11 through the spout 12 into that casting box 1, which at that time is in position adjacent the melting pot, as indicated in Figs. 1 and 2. The shaft 11^d could be rotated by hand, but is preferably operated automatically by means controlled by the box shifting mechanism.

In the construction shown, a sprocket gear 11^e is fixed on shaft 11^d; and a chain 11^f runs over this sprocket and has one end connected to a weight 11^s and its other end is connected to a crank pin or stud 7^a on a worm gear 7 journaled on a sub shaft 7^b mounted on a bracket or casting 13^e on the base 13. The worm gear 7 (see Figs. 3 and 4) meshes with a worm 8^a on a shaft

8, journaled in bearings 13^a (see Fig. 3) in the bracket 13^a, in line with but above shaft 6. On shaft 8 is splined a clutch member 8^b adapted to engage an opposed clutch member 9^b attached to a gear 9 which is rotatably mounted on the shaft 8. Gear 9 meshes with and is driven by a pinion 6^c on the shaft 6.

The clutch member 8^b should be held in engagement with the clutch member 9^b sufficiently long to cause one complete rotation of the gear 7 or one complete operation of the pump by suitable means. As shown, the hub 8^c of clutch member 8^b is annularly grooved and engaged by a bifurcated lever 18 which is pivoted on a stud 18^b attached to the casting 13^a, or a bracket thereon. Pivotedly mounted on stud 18^b is a lever 28, the long arm of lever 28 extending beside the gear 7 and being adapted to bear against the periphery of a cam disk 17 fixed to the gear 7 and having a single cam notch 17^a which is adapted to be engaged by the end of the lever 28 once for each rotation of gear 7. The lever 28 may be provided with a roller 28^a on its end to engage the periphery of the cam disk 17, and lever 28 is normally pressed upward, to hold its end yieldingly in engagement with the periphery of disk 17 by a spring 28^b which may be strung on a rod 28^c pivotally connected to the lever and depending through a guide opening in an adjacent part of or on the casting 13^a. The end of lever 28 will rise when it enters the cam notch 17^a, and the lever is held depressed when its end is disengaged from the cam notch but engaged with the periphery of cam disk 17.

Lever 28 has an upwardly projecting arm 28^e which lies opposite the upper end of lever 18, and a rod 18^e is pivotally connected with the upper end of arm 28^e and extends through an opening in the arm 18^b, and a compression spring 18^f is strung on the rod 18^e between the arm 18^b and a head or nut on the outer end of the rod 18^e as shown in Figs. 1, 3 and 4. This spring 18^f will cause the lever 18 to oscillate yieldingly with the lever 28, so that when the roller 28^a enters the cam notch 17^a the clutch member 8^b will be disengaged from the clutch member 9^b. When the roller 28^a is forced out of notch 17^a thereby depressing the long arm of lever 28, the clutch member 8^b will be engaged with clutch member 9^b, the spring 18^f affording the desired spring cushion between the clutch members.

The lever 28 has a short arm 28^f opposite its long arm which is connected by a link 29 to one arm of a bell crank lever 30 pivoted on an adjacent part of the support 13^a and the other arm of lever 30 is connected by a link 31 to one arm of a bell crank lever 32 pivoted at 32^a on a support, and the longer arm of said lever 32 projects beside

the periphery of the base of the turn table 2 and is adapted to be engaged by cams 2ⁿ attached to this turn table.

There is one cam 2ⁿ on the turn table for each casting box mounted thereon, and said cams 2ⁿ are so located that one of them will engage and depress the lever 32 just before a casting box comes into proper position beneath the spout 12. Upon such depression the lever 32 will, through the described 70 connections, oscillate lever 28 and disengage roller 28^a from notch 17^a, and throw clutch member 8^b into engagement with clutch member 9^b, whereupon motion will be transmitted to the worm gear 7; and lever 28 80 will be held positively depressed by the engagement of roller 28^a with the periphery of cam 17 until gear 7 has made a complete revolution and the roller 28^a again enters the notch 17^a. The cam 2ⁿ which just previously depressed the lever 32 being moved out of the way of the lever 32 just before the turn table comes to a stop.

Each time a casting box is brought to position to receive a charge of metal from the pump, the pump mechanism is automatically put into operation and will discharge a proper amount of fluid into the box to cast the plate. Upon completion of one cycle of operations the pump is automatically 95 stopped by the entry of the roller 28^a into the notch 17^a which permits spring 28^b to work lever 28 and disengage clutch member 8^b from clutch member 9^b.

When a plate is cast the operator can by 100 pulling the lever 5^a as described, throw the mechanism for moving the turn table again into operation, and it will automatically continue operating until the table is moved (in the example shown) 90°, when the table 105 again automatically comes to rest with another box in position to receive a charge of metal; and just before the turn table so comes to rest, the lever 32 would be again depressed by the proper cam 2ⁿ on the turn 110 table, and the pump operating means again set in motion and perform its cycle of operations.

The link 31 is preferably detachably engaged with the short arm of the lever 32, so that said link can be disengaged from the arm at will; and when so disengaged, the pump will not be operated automatically as described, but can be operated at the will of the operator, by his depressing a foot treadle 115 30^a attached to the bell crank lever 30.

The crank pin 7^a may be mounted on the gear 7 so as to be adjustable radially thereof in any suitable manner, as indicated in Fig. 6. By adjusting pin 7^a the extent of movement imparted to the pump plunger at each rotation of gear 7 can be so regulated that only the proper amount of metal will be pumped at each operation into the casting box to form the complete plate. For 125 130

each rotation of the gear 7 the pump plunger is first raised to expel the metal by the pull of the chain 11^c on crank pin 7^a and then is lowered as permitted by the movement of the crank pin 7^a.

What I claim is:

1. In apparatus of the character described, a turn table; a plurality of individual casting boxes mounted thereon; means for imparting a partial rotation to said turn table to bodily move the casting boxes thereon successively to and away from the casting point; a melting pot; a metal pump therein; means for conducting metal from the pump to the casting box in casting position; manually controlled means for releasing the turn table operating means when it is desired to shift the turn table; and means for automatically stopping the movement of the turn table when it has moved one box from casting position and brought another box into casting position.

2. In combination with mechanism as set forth in claim 1, mechanism for imparting one cycle of operation to the pump when a casting box is in casting position; and means controlled by the turning movement of the turn table for automatically releasing the pump operating means when a box is brought to casting position; and means for automatically stopping the operation of the pump actuating means when it has completed one operation.

3. In mechanism as set forth in claim 1; the means for operating the turn table comprising a shaft, gearing between the shaft and turn table; a clutch member splined to said shaft; an opposed clutch member; means for imparting continuous rotation to the latter clutch member; a lever for disengaging the one clutch member from the opposed clutch member; spring means for normally separating said clutch members, and means on the turn table for holding said lever in position to cause the engagement of the clutch members until the table is moved sufficiently to move one box away from casting position and the next box into casting position, said means permitting the spring to separate the clutch members when the latter box is moved to casting position.

4. In apparatus of the character described, a turn table; a plurality of individual casting boxes mounted thereon; means for imparting a partial rotation to said turn table to move the casting boxes thereon successively to and away from the casting point; a melting pot; a metal pump therein; means for conducting metal from the pump to the casting box in casting position; means for releasing the turn table operating means when it is desired to shift the turn table; and means for automatically stopping the movement of the turn table when it has moved one box from casting

position and brought another box into casting position; with mechanism for imparting one cycle of operations to the pump when the casting box is in casting position; means controlled by the turn table for automatically releasing the pump operating mechanism when a box is brought to casting position; and means for automatically stopping the operation of the pump operating mechanism when it has made one cycle of operation.

5. In mechanism as set forth in claim 4; the means for operating the turn table comprising a shaft, gearing between the shaft and turn table; a clutch member splined to said shaft; an opposed clutch member; means for imparting continuous rotation to the latter clutch member; a lever for disengaging the one clutch member from the opposed clutch member; spring means for normally separating said clutch members, and means on the turn table for holding said lever in position to cause the engagement of the clutch members until the table is moved sufficiently to move the box away from casting position and the next box into casting position, substantially as described.

6. In apparatus of the character described, a turn table; a plurality of individual casting boxes mounted thereon; means for imparting a partial rotation to said turn table to move the casting boxes thereon successively to and away from the casting point, comprising a worm gear connected with the table; a shaft adjacent the gear; a worm on said shaft engaging said gear; a clutch member splined to said shaft; an opposed clutch member rotatably supported on said shaft, means for imparting continuous rotation to the latter clutch member; a lever for disengaging the one clutch member from the opposed clutch member; said clutch members being normally disengaged; means on the turn table for holding said lever in position to cause the engagement of the clutch members and means for separating the clutch members and stopping the turn table each time a casting box is moved to casting position, substantially as described.

7. In combination with mechanism as set forth in claim 6; a melting pot; a metal pump therein; means for conducting metal from the pump to the casting box in casting position; manually controlled means for releasing the turn table operating means when it is desired to shift the turn table; and means for operating the pump once after a box is brought to casting position.

8. In apparatus of the character described, a turn table; a plurality of individual casting boxes mounted thereon; a worm gear connected with the table; a shaft adjacent the gear; a worm on said shaft engaging said gear; a clutch member

spined to said shaft; an opposed clutch member rotatably supported on said shaft, means for imparting continuous rotation to the latter clutch member; a spring pressed 5 lever for disengaging one clutch member from the opposed clutch member; the periphery of the turn table being adapted to hold said lever in position to cause the engagement of the clutch members and releases at the periphery of the turn table 10 adapted to be engaged by said lever to permit the spring to separate the clutch members each time a casting box is moved to casting position, substantially as described.

15 9. In combination with mechanism as set forth in claim 8, a melting pot; a metal pump therein; means for conducting metal from the pump to the casting box in casting position; manually controlled means for releasing the turn table operating means 20 when it is desired to shift the turn table; and means for automatically operating the pump once each time a box is moved to casting position.

25 10. In apparatus of the character specified, a turn table; a plurality of individual casting boxes thereon; and means for turning the table to bring the boxes successively to casting position; a metal pump, a shaft 30 for actuating the pump, a crank gear and connections for operating said shaft, a shaft for actuating the said crank gear; a clutch member spined to said shaft; an opposed clutch member; means for imparting continuous rotation to the latter clutch member; a spring pressed lever for disengaging 35 one clutch member from the opposed clutch member; and means on the turn table for holding said lever in position to cause the engagement of the clutch members until the pump has made one complete operation.

40 11. In mechanism as set forth in claim 10, a sprocket on the pump actuating shaft, and a sprocket chain engaging said sprocket and 45 connected at one end with the crank gear, and a weight on the other end of said chain, substantially as described.

50 12. In combination with mechanism as set forth in claim 10, means for automatically releasing the pump operating mechanism each time a box is moved to casting position.

55 13. In apparatus of the character specified, a turn table, a plurality of individual casting boxes thereon, and means for operating the turn table to bring the boxes successively to casting position; a metal pump, a shaft for actuating the pump, a crank gear and connections for actuating said shaft, a 60 shaft for actuating the said crank gear, gearing between the shaft and turn table; a clutch member spined to said shaft; an opposed clutch member; means for imparting continuous rotation to the latter clutch member; a lever for disengaging one clutch

member from the opposed clutch member; and a cam on the crank gear adapted to hold 70 said lever in position to cause the engagement of the clutch members until the pump has made one complete operation.

14. In mechanism as set forth in claim 13, a sprocket on the pump actuating shaft, a sprocket chain engaging said sprocket and connected at one end with a crank pin on 75 said crank gear, and a weight on the other end of the said chain, substantially as described.

15. In combination with mechanism as set forth in claim 13, a lever for manually controlling the box shifting means, and 80 means for automatically moving said lever to engage the clutch members each time a box is moved to casting position, substantially as described.

16. In combination, a pump; a crank and 85 connections for imparting reciprocatory movement to the pump plunger; a shaft and gearing for operating the crank; a clutch member mounted on the shaft; an opposed clutch member; means for rotating the latter clutch member; a disk having a peripheral cam notch; a lever having one arm 90 engaging the periphery of said disk and adapted to enter the notch; spring means for holding the lever in engagement with the cam; a member connected with said lever adapted to cause the clutch members to disengage when the lever is engaged with the notch in the disk; said disk holding 95 the clutch in engaged position until the lever reengages the notch; and means for disengaging the lever from the notch and shifting the clutch into engagement 100 whereby the pump mechanism is released to make one cycle of operation, substantially 105 as described.

17. In combination with mechanism as set forth in claim 16, a plurality of casting boxes, means for moving the boxes to and from casting position, means for manually 110 controlling the box shifting means, and means for automatically causing said lever to engage the clutch members each time a box is moved to casting position.

18. In combination with mechanism as set forth in claim 16, a turn table, a plurality of casting boxes thereon, means for shifting the turn table and means controlled by the turn table for automatically releasing the pump operating means each time a casting box is moved to casting position.

19. In combination with mechanism as set forth in claim 16, a turn table, a plurality of casting boxes thereon, means for shifting the turn table, and means controlled by the turn table for automatically causing said lever to release the pump operating means each time a casting box is moved to casting position; devices whereby the means for automatically starting the pump operat- 125 130

ing mechanism may be rendered ineffective; and devices for manually controlling the starting operation of the pump operating mechanism at the will of the operator.

5. 20. In apparatus of the character specified, a turn table, a plurality of casting boxes mounted thereon, a water supply pipe disposed axially of the turn table, radially disposed branches connected with said supply pipe and with the inlets of the water passages in the casting boxes; and outlet pipes connected with the outlets of the casting boxes, substantially as described.

15. 21. In apparatus of the character specified; a turn table, a plurality of casting boxes mounted thereon; a water supply pipe connected with the water inlets of the casting boxes; an outlet pipe disposed axially of the turn table, radially disposed pipes connected with the outlet pipe, and branched pipes connecting the radially disposed pipes with the water outlets of the casting boxes, substantially as described.

20. 22. In apparatus of the character specified, a turn table, a plurality of casting boxes mounted thereon, a water supply pipe disposed axially of the turn table, radially disposed branches connected with said supply pipe and with the inlets of the water pas-

30. sages in the casting boxes; an outlet pipe disposed axially of the table; and radially disposed pipes connecting the outlet pipe with the outlets of the casting boxes, substantially as described.

35. 23. In apparatus as set forth in claim 22, said radially disposed pipes respectively having swiveled connections with the inlet and outlet pipes, substantially as described.

40. 24. In apparatus of the character specified; a turn table; a plurality of casting boxes mounted thereon; a water supply pipe disposed axially of the turn table (radially disposed pipes connected with the supply pipe; branched pipes connecting the radially disposed pipes with the water inlets of the 45 casting boxes; an outlet pipe disposed axially of the turn table; radially disposed pipes connected with this outlet pipe; and branched pipes connecting the latter radially disposed pipes with the water outlets of the casting boxes, substantially as described.

50. 25. In apparatus as set forth in claim 24, said radially disposed pipes respectively having swiveled connections with the inlet and outlet pipes, substantially as described. 55

In testimony that I claim the foregoing as my own, I affix my signature.

HENRY F. BECHMAN.
